UNITED STATES PATENT OFFICE.

CHARLES BOSWORTH, OF BROOKLYN, NEW YORK.

DESIGN FOR A PICTURE-FRAME MOLDING.

SPECIFICATION forming part of Design No. 25,215, dated March 3, 1896.

Application filed January 31, 1896. Serial No. 577,626. Term of patent 8 $\frac{1}{2}$ years.

To all whom it may concern:

Be it known that I, CHARLES BOSWORTH, a citizen of the United States, and a resident of Brooklyn, in the county of Kings and State 5 of New York, have invented and produced a new and original Design for Picture-Frame Moldings and the Like, of which the following is a specification, reference being had to the accompanying drawing, forming part 10 thereof.

My design is for a frame or molding suitable for pictures, mirrors, and the like.

The essential features of my design consist in the configuration of the frame and the 15 surface ornamentation placed thereon, as shown in the drawing.

At A is the corner of the frame or molding, which is composed of curved leaves united at 20 their bases and diverging in the same direction, all of which are raised and in relief. The leaves B are all in relief, running in the same direction along and parallel with the

exterior of the frame or molding, with here and there a leaf, as shown at C, and foliated figures a between them. The outer surface 25 of the molding E is concavo-convex. The outer surface of the molding F is, as shown, provided with the bead or pearl-like ornamentation H placed thereon, as shown in the drawing. 30

The base of the molding is ornamented, as shown at D, in imitation of stipple-work.

Having thus described my invention, what I desire to secure by Letters Patent is—

The design for a picture-frame molding and 35 the like, substantially as shown and described.

Signed at the city of Brooklyn, county of Kings, and State of New York, this 24th day of January, 1896.

CHARLES BOSWORTH.
